(57) **CLAIM**

The ornamental design for a lubricant manifold as shown and described.

DESCRIPTION

FIG. 1 is a first isometric view of a first embodiment of a lubricant manifold;

FIG. 2 is a second isometric view of the first embodiment of the lubricant manifold;

FIG. 3 is a third isometric view of the first embodiment of the lubricant manifold;

FIG. 4 is a front elevational view of the first embodiment of the lubricant manifold;

FIG. 5 is a top plan view of the first embodiment of the lubricant manifold;

FIG. 6 is a right side view of the first embodiment of the lubricant manifold;

FIG. 7 is a left side view of the first embodiment of the lubricant manifold;

FIG. 8 is a rear elevational view of the first embodiment of the lubricant manifold;

FIG. 9 is a bottom plan view of the first embodiment of the lubricant manifold;

FIG. 10 is a first isometric view of a second embodiment of a lubricant manifold;

FIG. 11 is a second isometric view of the second embodiment of the lubricant manifold;

FIG. 12 is a third isometric view of the second embodiment of the lubricant manifold;

FIG. 13 is a front elevational view of the second embodiment of the lubricant manifold;

FIG. 14 is a top plan view of the second embodiment of the lubricant manifold;

(Continued)

FIG. 15 is a right side view of the second embodiment of the lubricant manifold;
 FIG. 16 is a left side view of the second embodiment of the lubricant manifold;
 FIG. 17 is a rear elevational view of the second embodiment of the lubricant manifold;
 FIG. 18 is a bottom plan view of the second embodiment of the lubricant manifold;
 FIG. 19 is a first isometric view of a third embodiment of a lubricant manifold;
 FIG. 20 is a second isometric view of the third embodiment of the lubricant manifold;
 FIG. 21 is a third isometric view of the third embodiment of the lubricant manifold;
 FIG. 22 is a front elevational view of the third embodiment of the lubricant manifold;
 FIG. 23 is a top plan view of the third embodiment of the lubricant manifold;
 FIG. 24 is a right side view of the third embodiment of the lubricant manifold;
 FIG. 25 is a left side view of the third embodiment of the lubricant manifold;
 FIG. 26 is a rear elevational view of the third embodiment of the lubricant manifold; and,
 FIG. 27 is a bottom plan view of the third embodiment of the lubricant manifold.
 The broken lines in the drawings depict portions of the lubricant manifold that form no part of the claimed design.
